FINGER RING

Adolph Katz, Providence, R.I., assignor to Coro, Inc., of Rhode Island, Providence, R.I., a corporation of Rhode Island

Filed Sept. 3, 1963, Ser. No. 76,444

Term of patent 3½ years

(Cl. D45—10)

FIG. 1

FIG. 2

FIG. 3

FIG. 4

FIG. 1 is a perspective view of a finger ring showing my new design;

FIG. 2 is a top plan view thereof;

FIG. 3 is a side elevational view thereof; and

FIG. 4 is an end elevational view thereof.

The florentine pattern continues across the top in FIG. 1 as disclosed in FIGS. 2, 3 and 4.

The dominant features of my design reside in the full-line portions of the drawing.

I claim:

The ornamental design for a finger ring, substantially as shown and described.
